UNITED STATES PATENT OFFICE.

CESARE BARBIERI, OF NEW YORK, N. Y., ASSIGNOR TO THE VORTEX MFG. CO., OF CHICAGO, ILLINOIS, A CORPORATION OF ILLINOIS.

NESTED-FLAT-CUP CARTON AND FILLER.

Application filed October 31, 1924. Serial No. 746,974.

This invention relates to an improved 5 filler member for use in combination with a stack of nested flat cups to serve as a holder when the stack of cups is inserted into a carton or into a dispenser and further adapted to act as a guide for the flap of the cover of a carton when the carton is closed after a stack of nested cups has been deposited therein.

10 It is an object of this invention to provide a filler for use in connection with a stack of flat nested cups.

It is also an object of the invention to provide a folded filler adapted to be engaged 15 on a stack of flat nested cups to shield the cups against holding contact by the fingers of a person inserting a stack of cups into a carton.

It is a further object of the invention to 20 provide a cardboard holder adapted to be engaged on one side of the open end of a stack of flat nested cups to obviate the necessity of the fingers of a person from contacting the rim margins of the cups when the 25 stack of cups is being removed from a carton and inserted in a cup dispenser.

It is an important object of this invention to provide a filler member for use in combination with a stack of flat nested cups 30 to facilitate the handling of the stack of cups for insertion into a carton and also serving as a guide to permit the cover flap of the carton to be readily inserted in place without any danger of injuring the margins 35 of the nested cups.

Other and further important objects of this invention will be apparent from the disclosures in the specification and the accompanying drawings.

40 The invention (in a preferred form) is illustrated in the drawings and hereinafter more fully described.

On the drawings:

Figure 1 is a front elevation of a carton 45 provided with a filler member embodying the principles of this invention.

Figure 2 is an enlarged transverse detail section taken on line 2—2 of Figure 1.

Figure 3 is an enlarged detail section 50 taken on line 3—3 of Figure 1.

Figure 4 is a front elevation of a cup dispenser illustrating the method of inserting a stack of flat nested cups by means of the improved filler.

As shown on the drawings:

The reference numeral 1 indicates a cardboard carton having a pair of side flaps 2 and a cover 3. The cover 3 is provided with a hinged flap 4 adapted to be inserted into the carton when the cover is positioned to close the carton. Both ends of the carton may be constructed alike if so desired.

55 The carton 1 is adapted to serve as a receptacle for a stack of flat nested paper cups 5 with the cups seated one within the other in compact form for packing in the carton ready for storage or shipment.

60 Seated in the uppermost cup is a holder or filler made of cardboard or other suitable material and comprising a back plate 6 and a hinged apron or flap 7. A dispenser 8 is illustrated for the purpose of showing 65 how the filler 6—7 is used when a stack of flat nested cups is inserted in the dispenser.

70 The cups 5 when formed are delivered 75 from a cup forming machine in nested relation marked off in predetermined quantities so that a filler 6—7 may readily be inserted in its proper place to permit a stack of 80 cups to be engaged by the hands of an operator as illustrated in Figure 4 and lifted from the machine table for insertion into the open end of a carton 1. The filler back plate 6 acts as a separator and guide and is positioned between the inner face of the 85 front wall of the carton and the upper portion of the stack of cups as illustrated in Figure 2. When the carton is filled the filler is left in its place and the carton side flaps 2 are folded inwardly after which 90

95 the cover 3 is closed by inserting the cover flap 4 between the upper end of the front wall of the carton and the filler 6—7. The filler thus serves as a guide for the cover flap and as a protector for the cups against injury from the cover flap 4, which without the use of the filler, very often is pushed against the edges of the cups and tends to wrinkle, dent or otherwise injure the same.

100 The stack of cups 5 is inserted in the top of the dispenser point downward as shown in Figure 4 using the filler 6—7 as a shield. One hand of a person engages the filler while the person's other hand engages the lowermost cup as indicated. The stack of cups is thus pushed into the dispenser 8 until it is filled with the tip of the lowermost cup projecting through the apertured 105

bottom of the dispenser ready to be withdrawn. When the stack of cups is properly placed in the dispenser the filler is used so that the hands of a person do not come into contact with the rims of the cups. The filler may be removed after the dispenser is filled.

I am aware that many changes may be made and numerous details of construction 10 may be varied through a wide range without departing from the principles of this invention, and I therefore do not purpose limiting the patent granted hereon, otherwise than necessitated by the prior art.

15 I claim as my invention:

1. The combination with a stack of flat nested cups, of a filler member adapted to be engaged over one side and project into the open end of the stack of cups to facilitate handling of said stack of cups.

2. The combination with a stack of flat nested cups, of a folded filler adapted to be projected into said stack of cups to serve as a holder in handling the stack of cups.

25 3. The combination with a stack of cups, of a filler member comprising a back plate adapted to be positioned against the exterior of the stack of cups, and a flap on said back plate adapted to project into the cup at the upper end of the stack.

30 4. The combination with a carton and a

stack of nested cups, of a filler member adapted to be engaged on the stack of cups with a portion of the filler member positioned between the stack of cups and the carton and another portion of said filler member projecting into the uppermost cup in the carton.

35 5. The combination with a carton having a cover with a flap, of a stack of nested cups, 40 and a filler adapted to be engaged in the stack of cups to facilitate holding the stack of cups for insertion into the carton, said filler adapted to be projected into the carton with the stack of cups and have a flap 45 thereof serve as a guide for the cover flap and obviate injury to the rims of the cups by said cover flap.

6. The combination with a carton having a cover with a flap, said carton adapted to 50 receive a stack of flat nested cups, and means adapted to be inserted in the carton and into the stack of cups to serve as a guide for the cover flap.

7. A cup stack handling device comprising 55 a plate having a curved edge, and a tapered flap hinged to said plate opposite the curved edge thereof and adapted to be projected into a stack of cups.

60 In testimony whereof I have hereunto subscribed my name.

CESARE BARBIERI.
